UNITED STATES PATENT OFFICE.

JOHN H. WIGGINS, OF BARTLESVILLE, OKLAHOMA.

LIQUID-STORAGE TANK.

Original application filed May 19, 1922, Serial No. 562,107. Divided and this application filed February 16, 1924. Serial No. 693,397.

To all whom it may concern:

Be it known that I, JOHN H. WIGGINS, a citizen of the United States, residing at Bartlesville, Oklahoma, have invented a 5 certain new and useful Improvement in Liquid-Storage Tanks, of which the following is a full, clear, and exact description, such as will enable others skilled in the art to which it appertains to make and use 10 the same.

This invention relates to liquid storage tanks of the type in which the top or deck of the tank is not connected to the side wall of the tank, but normally floats upon and is 15 supported by the liquid in the tank, my present application being a division of my application for patent Serial No. 562,107, filed May 19, 1922.

One object of my present invention is to 20 provide a liquid storage tank that is equipped with an efficient means of novel construction for sustaining the deck when said deck is not supported by the liquid in the tank.

25 Another object is to provide a novel means for bracing the side wall of a liquid storage tank against wind pressure.

Figure 1 of the drawings is a top plan view of a liquid storage tank constructed in 30 accordance with my invention.

Figure 2 is a vertical transverse sectional view of said tank; and

Figures 3 and 4 are sectional views, illustrating certain details of construction of 35 said tank.

Referring to the drawings, A designates a vertically-disposed, cylindrical member open at its upper end, that constitutes the side wall of the tank, B designates the bottom 40 of the tank and C designates the top or deck of the tank which normally floats upon and is supported by the liquid in the tank. The side wall of the tank is braced against wind pressure and maintained in circular shape by radially-disposed tension members B connected at their outer ends to vertically-disposed projections 1 on the side wall A and connected at their inner ends to a collar 2 on the upper end of a vertically-disposed mast or upright 3 that projects upwardly from the bottom of the tank at the center of the tank, said tension members D being preferably provided with turn-buckles 4 or other suitable adjusting devices.

55 The deck C is of rigid construction and is

composed of horizontally-disposed sheet metal plates 5 rigidly connected together and reinforced by radially-disposed members 6, preferably I-beams, or other type of girders that simply rest upon the plates 5 or which are secured to said plates and also to a center piece 7 preferably in the form of a sleeve up through which the mast 3 extends.

Means is provided for sustaining the deck 65 C when said deck is not supported by the liquid in the tank, and while said means can be constructed in various ways without departing from the spirit of my invention, I prefer to equip the tank with removable 70 hanger rods 8 adapted to be arranged at the side wall of the tank and at the center of the tank and constructed in such a manner that they can be detachably connected to the deck, to the mast 3 and to the projections 1 75 at the upper edge of the side wall A of the tank. For example, the hanger rods 8 adjacent the side wall of the tank can have their upper ends detachably connected to the projections 1 by removable U-bolts or 80 other suitable devices 9 on the projections 1, as illustrated in Figure 3, and said hanger rods can be detachably connected at their lower ends to U-bolts or other suitable devices 10 arranged adjacent the periphery of 85 the deck C, as shown in Figure 4. The hanger rods 8 at the center of the tank can be detachably connected at their upper ends to the collar 2 on the mast 3 and detachably connected at their lower ends to devices on 90

the center piece or sleeve 7 of the deck up through which the mast 3 extends. The hanger rods can be equipped with turn-buckles or other suitable devices for varying the length of said hanger rod. When the 95 tank is empty the deck can be sustained in a horizontal position parallel to the bottom of the tank by means of the hanger rods 8, and when it is desired to float the deck on the liquid in the tank, the hanger rods are disconnected from the deck and removed from the tank.

The deck C is provided at its peripheral edge with an upwardly-projecting rim 11, and any suitable means can be used for closing the annular space between said rim and the side wall of the tank, the means illustrated in Figure 4 for closing said space consisting of a shoe E arranged in sliding engagement with the side wall of the tank 110

and supported in any suitable manner on the rim 11 of the deck, and a mass of asbestos or other suitable fire-proof material G of a sponge-like nature arranged between 5 said shoe and said rim. As the level of the liquid in the tank varies the shoe E slides up and down on the inner surface of the side wall of the tank, and when the level of the liquid in the tank is such as to cause the upper edge portion of the shoe E to project 10 above the top edge of the side wall A of the tank, the upwardly-projecting devices 1 on said side wall to which the tension members D are connected serve as guides for the 15 upper edge portion of the said shoe.

Having thus described my invention, what I claim as new and desire to secure by Letters Patent is:

1. A liquid storage tank provided with a 20 side wall formed by a vertically-disposed, cylindrical member open at its upper end, a vertically-disposed mast or upright at the center of the tank, devices projecting upwardly above the top edge of said side wall,

radially-disposed tension member connected 25 at their inner ends to said mast and at their outer ends to said devices, and a floating deck supported by the liquid in the tank and provided with a shoe whose upper edge portion slides upon said upwardly-projecting 30 devices under certain conditions.

2. A liquid storage tank, comprising a cylindrical side wall, a floating deck adapted to normally rest upon the liquid in the tank, a mast or upright at the center of the tank 35 that projects upwardly through said deck, devices projecting upwardly from the top edge of the side wall of the tank, radially-disposed tension members connected at their inner ends to said mast and at their outer 40 ends to said upwardly-projecting devices, and a temporary sustaining means for the deck comprising hanger rods adapted to be arranged at the center and at the side walls of the tank and detachably connected at their 45 ends to said mast and to the upwardly-projecting devices on the side wall.

JOHN H. WIGGINS.
